UNITED STATES PATENT OFFICE.

JOHN R. KELLER, OF PITTSBURG, PENNSYLVANIA.

RAILWAY-TIE PLATE.

No. 906,033.

Specification of Letters Patent.

Patented Dec. 8, 1908.

Application filed August 21, 1907. Serial No. 389,552.

To all whom it may concern:

Be it known that I, JOHN R. KELLER, a resident of Pittsburg, in the county of Allegheny and State of Pennsylvania, have invented a new and useful Improvement in Railway-Tie Plates; and I do hereby declare the following to be a full, clear, and exact description thereof.

My invention relates to railway tie-plates and its object is to provide a tie-plate which is so constructed that it will not rock on its center, and which can be easily seated and held against longitudinal and lateral movement on the tie, and which can be easily and cheaply manufactured.

Tie-plates commonly in use have not been found wholly satisfactory because of their tendency to move and rock on the tie under traffic, thus forming an unstable bearing for the rail, with a consequent loosening and wear of the rail holding spikes and destruction of the fibers of the tie, whereby the point of support for the rail is weakened.

Tie-plates with various forms of means for attaching them to the tie to prevent these difficulties have been devised, the prevailing form being those with claws or flanges on their lower surfaces adapted to be driven into the tie either parallel or transverse with the grain of the wood. In the longitudinal flange construction with flanges of uniform depth, the rolling action and vibrations of the rail cause the plate to rock on its center and its ends to cut into the fibers of the tie, and wear and loosen the spikes, and if deep flanges are employed, there is liability to split and check the tie beyond the ends of the plate, allowing moisture to get into and decay the tie. With the use of flanges or claws transversely of the plate, the fibers of the tie are severed in seating the plate, which causes decay. It has also been found that the continued pounding or impinging of the rail on the plate through traffic will soon cause the flanges to form enlarged grooves and compact the fibers of the tie so that there is not sufficient friction between the wood and the flanges to hold the plate against movement. These special forms of tie-plates are difficult and expensive to manufacture, especially those rolled of steel, requiring special rolls and many passes through the rolls to break down the billet and form the flanges, making the labor

cost large. A form of tie-plate that can be made cheaper and maintain its position on the tie, and of sufficient strength to support the rail properly, is therefore desirable. My invention is designed to provide a tie-plate which will prevent these difficulties, and which can be easily and cheaply manufactured from flat plate, and have all the advantages of the special rolled and more expensive forms of plates, besides several other advantages.

The invention comprises a plate such as hereinafter described and claimed.

In the accompanying drawings Figure 1 is a perspective view of the tie-plate; Fig. 2 is a similar view showing the plate inverted; Fig. 3 is a vertical section taken transversely through the rail and longitudinally of the tie showing the tie-plate in elevation between the base of the rail and tie; Fig. 4 is a cross-section on the line 4-4 of Fig. 1; Fig. 5 is a cross section on the line 5-5 of Fig. 1; Fig. 6 is a perspective view showing the invention applied to a top shouldered plate; and Fig. 7 is a perspective bottom view of another form of plate.

My invention in its preferred form comprises a flat body portion 1, although this body portion may be corrugated, ribbed, or any desired cross section, and of any suitable thickness, but I prefer to make the body portion flat, affording large surface contact with the rail and tie, and requiring no special form of rolls to form the plate, but the manufacturer can buy flat plate of the required width and gage on the open market, from which the plate is formed. The body portion is provided with the usual spike receiving holes 2, punched to meet the requirements of the different railroads, and usually just outside of the rail base zone and diagonally on the plate. Through these holes are driven the rail-holding spikes 3, as shown in Fig. 3, adapted to receive the lateral thrust of the rail under traffic, the outside wall of the hole providing a backing for the spike in absence of a top flange or shoulder in the plate, such a shoulder being shown at 11 in Fig. 6. It is essential that in absence of a shoulder or like means, the plate should be held against longitudinal movement on the tie to properly support the spike to resist the thrust of the rail, and it has been found that the form of flanges now em-

ployed on the bottom of the plate do not provide sufficient resistance against movement or attach themselves to the tie to assist the spike. This is due to the shallowness of the flanges, as deep flanges cannot be used on account of their liability to split the tie, and the large number employed destroy the resiliency of the fibers. The body portion of the plate is provided with depending flanges 5, preferably located at the sides of the plate and extending longitudinally of the plate. If desirable, these flanges may be of thickness their full depth equal to the thickness of the body portion, but I prefer to bevel or 15 scarf the outside face of the flanges as at 6 to facilitate the insertion of the flanges in the tie, and having the inside faces 7 of the flanges vertical or at right angles to the plane of the body portion, which provides 20 against rupture of the fibers between the flanges under the body portion. If desirable to use a cast or forged plate of thin cross - section, requiring reinforcement against buckling, intermediate flanges 5^a may 25 be used as shown in Fig. 7. In order to prevent the rocking of the plate on its transverse center, the flanges are arranged with oppositely diverging flat bottom edges 8, having their extreme depth at the ends of 30 the plate, as at 9, and gradually reducing in depth to a point at the center and bottom surface of the plate, as at 10. These flat bottom edges of the flanges are at right angles to the inner vertical faces of the flanges. 35 The cutting away of the flange at its center not only prevents the rocking of the plate, but also prevents movement of the plate longitudinally of the tie, as it is obvious that the wood between the inclined flat bottom edges 8 of the flanges must be displaced or 40 the plate raised above this obstruction in order to move longitudinally on the tie. The flat inclined surfaces 8 prevent the flange from cutting into the tie under lateral stresses applied to the rail, and hence 45 provide efficient means for holding the plate against movement longitudinally of the tie. As the plate settles into the tie, it maintains its position against movement in either direction longitudinally, as the wood is compressed between the inclined flat bottom edges of the flanges. The plate not only 50 provides flanges easy to embed and hold the plate against movement, but in addition, 55 reinforce the plate at a point subject to buckling strains. These flanges are of only slight depth underneath the rail base and hence mutilate the wood as little as possible at the point where the load is applied. Since 60 the inner faces of the flanges are vertical, the cutting of such flanges through the fiber forms a vertical shear on the portion underneath the plate and therefore distorts and destroys the fiber of the wood under the

plate very little. This is important, as it 65 leaves the solid wood underneath the plate where the load is applied. The deep outer ends of the flanges form prongs which embed themselves in the tie and hold the plate from rising. These prongs are removed as 70 far as possible from the edges of the rail base and hence entirely overcome any tendency of the plate to rock.

The preferred form of plate described is very cheap to manufacture, as it is formed 75 from flat plate bought on the open market, and the forming thereof merely requiring punching the holes, shearing and turning the flanges, all of which can be done at a single 80 operation.

What I claim is:

1. A tie plate comprising a body portion having on its lower surface flanges adapted to engage the tie, said flanges having their 85 lower edges inclined toward both ends of the plate and having their extreme depth at the ends of the plate.

2. A tie plate comprising a body portion having on its lower face flanges adapted to engage the tie, said flanges having their 90 lower edges inclined from the center and bottom surface of the plate to their extreme depth at the ends of the plate and having vertical end faces.

3. A tie plate comprising a body portion 95 having on its side edges tie engaging flanges increasing in depth from the center of the plate outwardly and having their extreme depth at the ends of the plate, said flanges having their inner faces at right angles to 100 the plane of the body portion of the plate.

4. A tie plate comprising a body portion having on its side edges tie engaging flanges increasing in depth from the center of the plate outwardly and having their extreme 105 depth at the ends of the plate, said flanges having their inner faces at right angles to the plane of the body portion of the plate and having outside beveled faces.

5. A tie plate comprising a body portion 110 having on its side edges tie engaging flanges increasing in depth from the center of the plate outwardly and having their extreme depth at the ends of the plate, said flanges having their inner faces at right angles to the 115 plane of the body portion of the plate, and having their lower edges flat and at right angles to said inner vertical faces.

6. A tie plate comprising a body portion having on its lower faces flanges adapted to 120 engage the tie, said flanges having their lower edges diverging in opposite directions longitudinally, said lower edges transversely of the flanges being substantially parallel to the plane of the body of the plate.

7. A tie plate comprising a body portion having on its lower surface flanges for entering the tie, said flanges increasing in depth 125

from the center of the plate outwardly and having their extreme depth at the ends of the plate and having flat lower edges.

8. A tie plate comprising a body portion having on its lower surface tie engaging flanges increasing in depth from the center of the plate outwardly and having their extreme depth at the ends of the plate, said

flanges having flat bottom edges and vertical end faces.

In testimony whereof, I the said JOHN R. KELLER, have hereunto set my hand.

JOHN R. KELLER.
